ROCK BIT

Alfred C. Catland, Alhambra, Calif., assignor to
 Globe Oil Tools Company, Los Nietos, Calif., a
 corporation of California

Application January 8, 1937, Serial No. 119,615

9 Claims. (CL 255—71)

This invention relates to well drilling tools and relates more particularly to a rock bit for use in the rotary method of well drilling. A general object of this invention is to provide a practical dependable rock bit embodying novel anti-friction mountings for the cutters.

Another object of this invention is to provide improvements in the type of bit construction described and claimed in my co-pending application entitled Well bit cutter mounting, Serial No. 102,527, filed September 25, 1936, now Patent No. 2,111,753, granted March 22, 1938.

Another object of this invention is to provide a well bit embodying inner roller cutters and long wearing anti-friction bearing means rotatably supporting the inner cutters.

Another object of this invention is to provide a rock bit of the character mentioned in which the bearing means for supporting the inner cutters dependably supports the inner cutters against end thrusts in both directions to prevent the development of end play and excessive wear on the end surfaces of the cutters.

Another object of this invention is to provide a rock bit of the character mentioned in which series of balls rotatably support the inner cutters against radial thrusts and end thrusts in both directions, assuring free rotation of the cutters and preventing end wear and play of the cutters.

Another object of this invention is to provide an anti-friction mounting for the roller cutters of a well bit in which separate series of balls assume the opposing end thrusts.

Another object of this invention is to provide a roller cutter mounting in which the cutter supporting pin and the bushings are prevented from chattering and hammering one against the other.

Another object of this invention is to provide a rock bit embodying novel and improved means for removably securing the inner cutter assembly to the shank or body of the bit.

A further object of this invention is to provide a rock bit of the character mentioned in which the inner cutter assembly comprising the several inner cutters, the bearings and the supporting pin may be installed and removed as a unit.

The various objects and features of my invention will be fully understood from the following detailed description of a typical preferred form and application of the invention, throughout which description reference is made to the accompanying drawings, in which:

Fig. 1 is a side elevation of the bit provided by this invention illustrating the principal lower

portion in vertical cross-section to show the mountings of the outer cutters and Fig. 2 is a side elevation of the bit with the lower principal portion in vertical cross-section to illustrate the mountings of the inner cutters.

The improved well bit of the present invention includes, generally, a shank or body 10, outer cutting means 11 on the body 10 and inner cutting means on the body comprising a shaft or pin 12 removably secured to the body 10, two sets or 10 pairs of cutters 13 and 14 and bearing means 15 rotatably supporting the cutters 13 and 14 on the pin 12.

The shank or body 10 of the bit is intended to be connected with the lower end of a rotary well 15 drilling string. In practice the body 10 may be an integral member, as illustrated. A tapered screw threaded pin 16 may be provided on the upper end of the body 10 to facilitate its connection with the rotary drilling string. A substantially central web 17 projects downwardly from the lower end of the body 10 and carries two downwardly and outwardly projecting wings 18. Outer wings 19 project downwardly and outwardly from the body 10 in spaced substantially 25 parallel relation to the wings 18. The outer lower corners 20 of the wings 19 are cut off to be substantially vertical. The body 10 further includes two diametrically opposite legs 21 projecting downwardly from its lower end. The legs 30 21 are spaced substantially 90° from the wings 19 and their lower portions are substantially vertical being only slightly pitched downwardly and outwardly. A central vertical fluid passage 22 enters the body 10 from the upper end of its pin 35 16. The lower end of the passage 22 joins a chamber 23 in the body 10. Discharge ports 24 are provided in the lower wall of the body 10 to discharge the fluid downwardly from the chamber 23 against the cutters. Replaceable wear taking 40 nozzles or beans 25 line the ports 24.

The outer cutting means 11 include outer cutters 26 rotatably supported between the pairs of wings 18 and 19 to act on the outer portion of the well bore to cut the bore to gauge. The cutters 26 are in the nature of roller cutters and may be slightly conical as illustrated. Suitable peripheral cutting teeth 27 are provided on the cutters 26. The outer ends of the teeth 27 are bevelled off to be substantially vertical as the 50 teeth come into engagement with the formation at the bottom of the well bore. Each cutter 26 is provided with a central longitudinal opening 28.

The outer cutting means 11 further include 55

pins 29 passed outwardly through openings 30 in the wings 18 to have their outer portions threaded in openings 31 in the wings 19. The pins 29 have suitable heads at their inner ends bearing outwardly against the inner sides of the wings 18. Plain or unthreaded parts may be provided on the outer ends of the pins 29 and these parts may be peened into notches 32 in the outer sides of the wings 19 to prevent unthreading and dis-
5 placement of the pins. The openings 30 and 31 are inclined downwardly and inwardly relative to the vertical axis of the bit so that the pins 29 extend at substantially right angles to the opposing surfaces of the wings 18 and 19.

10 The pins 29 of course extend through the openings 28 of the cutters 26 and each pin carries a pair of bushings 33 and 34. The opposing ends of the bushings 33 and 34 preferably abut. The inner ends of the bushings 33 bear inwardly against the wings 18 while the outer ends of the bushings 34 bear outwardly against the wings 19. Lugs 35 are provided on the bushings 33 to co-
15 operate with the lower ends of the wings 18 to prevent turning of the bushings and to assist in transmitting thrusts from the bushings to the wings. Each bushing 33 is provided at its inner end with a radial annular flange 36 which bears against the adjacent wing 18. The corners occurring between the flanges 36 and the bodies 20 of the bushings 33 are spherically concaved to constitute ball races 37. The outer bushings 35 are provided with annular radial flanges 38 which bear against the inner sides of the wings 19. The corners occurring between the flanges 38 and the bodies of the bushings 34 are spherically concaved to 25 constitute ball races 39. It will be observed that the bodies of the outer bushings 34 are somewhat larger in diameter than the bodies of the inner bushings 33 so that the races 30 39 are somewhat larger in circumference than the races 37. Lugs 40 may be provided on the bushings 34 or their flanges 38 to cooperate with the lower ends of the wings 19 to prevent rotation of the bushings and to assist in transmitting 35 operating thrusts from the bushings to the wings. The flanges 36 and 38 bearing on the opposing surfaces of the wings 18 and 19 are received or partially received in the opposite ends of the cutter openings 28 and may serve to close the ends 40 of the openings.

50 The means for rotatably supporting the cutters 26 include annular ribs 41 on the walls of the cutter openings 28. The ribs 41 are spaced between the ends of the cutters 26. The inner sides of the ribs 41 are spherically concave and constitute ball races 42 which oppose the above described races 37. The outer sides of the ribs 41 are spherically concave to constitute ball races 43 which oppose the above described races 39. It is to be noted that center lines extending through the centers of the opposing races 37 and 42 and center lines extending through the opposing races 39 and 43 are pitched relative to the longitudinal axes of the pins 29, the lines extending through the races 37 and 42 being pitched in one direction and the lines extending through the races 39 and 43 being pitched in the other direction.

55 In accordance with the invention series of balls 44 surround the bushings 33 to cooperate with the races 37 and 42 and series of balls 45 surround the bushings 34 to cooperate with the races 39 and 43. The balls 45 are considerably larger than the balls 44 to assume the principal vertical operating thrusts as well as the outwardly directed end thrusts applied to the cutters 26.

60 The series of balls 44 and 45 rotatably support the cutters 26 on the bushings 33 and 34 to assume all of the radial thrusts from the cutters. The above described relationship between the races 37 and 42 is such that the balls 44 transmit the inward end thrusts from the cutters 26 and assist in transmitting the radial thrusts from the cutters. The races 39 and 43 are related so that the balls 45 transmit the outward end thrusts from the cutters 26 and assist in transmitting the radial thrusts from the cutters. The cutters 26 are entirely rotatably supported by the series of balls 44 and 45 and their ends do not bear on the wings 18 and 19 of the body 10. The cutters 26 rotatably mounted, as just described rotated about downwardly and inwardly inclined axes and project downwardly and outwardly beyond the lower ends of the wings 18 and 19 to act on the outer portion of the well bore and cut the bore to gauge.

65 The inner cutting means constitutes the assembly of the pin 12, the cutters 13 and 14 and the bearing means 15 which assembly may be attached to the body 10 and removed from the body as a single unit. The inner cutting means is arranged between the diametrically opposite legs 21 at the lower end of the body 10. The pin 12 is the supporting element of the inner cutting assembly. The pin 12 is an elongate integral part whose end portions or principal portions are 70 inclined downwardly and outwardly from an intermediate portion 46. The intermediate portion 46 of the pin 12 is thickened or enlarged and has flat sides and a flat substantially horizontal upper surface 47. The lower end of the body web 17 is provided with an opening or notch 48 shaped to receive the enlarged portion 46 of the pin 12. The upper surface 47 of the pin enlargement 46 is adapted to bear upwardly against the wall of the notch 48 for the transmission of the vertical 75 thrusts from the pin 12 to the body 10. The opposite ends 49 of the enlarged pin portion 46 are downwardly convergent and constitute substantially normal shoulders at the inner ends of the principal cutter carrying portions of the pin 12.

80 The invention provides novel effective means for removably securing the enlarged intermediate portion 46 of the pin 12 to the body 10. A cap screw 50 is passed downwardly through a vertical opening 51 in the web 17 and its lower portion is threaded into a socket 52 in the thickened portion 46 of the pin 12. The head of the cap screw 50 is received in the upper portion of the opening 51 and a rubber washer 52a is provided under the head of the screw to prevent 85 the leakage of the circulation fluid about the screw. Means is provided for preventing unthreading of the cap screw 50. A plate 54 is welded to the lower wall of the chamber 23 to extend across the upper end of the opening 51. A 90 polygonal pin 55 is force-fitted in a correspondingly shaped opening in the plate 54 to extend into the polygonal socket in the end of the cap screw 50. The pin 55 fitting the socket in the cap screw 50 positively prevents unthreading of 95 the screw. The plate 54 and the pin 55 are accessible through the passage 22.

100 The cutter supporting pin 12 projects radially outward in both directions from adjacent the center of the bit to have its opposite ends adjacent the inner sides of the legs 21. The ends of the pin 12 are preferably spaced from the inner sides of the legs 21. Screws 56 are passed inwardly through openings 57 in the legs 21 and have their inner portions threaded in sockets 58 105

in the ends of the pin 12. The screws 56 secure the ends of the pin 12 to the legs 21 of the body 10. The heads of the screws 56 are countersunk in the openings 57. The heads of the screws 56 may have parts peened into notches 58a in the outer sides of the legs 21 to prevent loss or unthreading of the screws. In accordance with the invention the pin 12 is graduated to have annular outwardly facing shoulders 59 spaced between the enlarged portion 46 and the outer ends of the pin.

The inner cutters 13 and 14 are provided to act on the inner portion of the well bore and are arranged in pairs, there being one cutter 13 and one cutter 14 on each principal portion of the pin 12. The innermost cutters 13 are cylindrical roller cutters provided with peripheral cutting teeth 60. The opposite ends of the cutters 13 may be plain and flat. The teeth 60 preferably overhang or project inwardly beyond the inner ends of the cutters 13 to act on the earth formation immediately adjacent the center of the well bore as will be hereinafter described. An annular rib 61 is provided on the interior of each cutter 13. The inner and outer sides of the ribs 61 are spherically concaved to constitute ball races 62 and 63, respectively.

The cutters 14 are frusto-conical roller cutters arranged around the outer portions of the pin 12 with their small ends facing inwardly. The cutters 14 are somewhat larger in diameter than the innermost cutters 13. The opposite ends of the cutters 14 may be plain and flat. Suitable peripheral cutting teeth 64 are provided on the cutters 14. The cutters 14 are tubular having central longitudinal openings 65. An annular flange or rib 66 is provided on the wall of each cutter opening 65. The ribs 66 are spaced a short distance from the inner ends of the cutters 14. The inner and outer sides of the ribs 66 are spherically concave to constitute ball races 67 and 68, respectively. A third spherically concaved ball race 69 is provided on the interior of each cutter 14. The races 69 are adjacent the outer ends of the cutters 14 and face outwardly, as illustrated in the drawings.

The bearing means 15 are features of the invention. The bearing means 15 include washers or bushings 70 at the outer ends of the pin 12. The bushings 70 engage against inner sides of the body legs 21 and fit around the screws 56. The openings 71 through the bushings 70 receive the outer end portions of the pin 12. When the screws 56 are tightened down they clamp the bushings 70 between the ends of the pin 12 and the inner sides of the legs 21. The bushings 70 are provided with radial flanges 72 which bear against the inner sides of the legs 21. The flanges 72 are partially received in the outer ends of the openings 65 in the cutters 14. Welds 73 rigidly connect the lower portions of the flanges 72 with the lower ends of the legs 21. The welds 73 rigidly secure the bushings 70 to the legs 21 to prevent chattering of the bushings and the end portions of the pin 12. The corners occurring between the flanges 72 and the bodies of the bushings 70 are spherically concaved to constitute ball races 74. The races 74 oppose the races 69 on the interiors of the cutters 14.

The bearing means 15 further includes annular series of balls 75 surrounding the bushings 70 to cooperate with the races 69 and the races 74. The races 69 and 74 are related so that a line drawn through the points of contact of a ball 75 with the races is pitched relative to the

longitudinal axis of the pin 12 in such a manner that the balls 75 assume outward end thrusts on the cutters 14, as well as radial thrusts on the cutters. The bearing means 15 include annular series of balls 76 cooperating with the races 68 on the interiors of the cutters 14 and directly bearing on the pin 12. The inner ends of the bushings 70 may contact or engage the balls 76 to hold them in position. The balls 76 may assume some of the radial thrusts on the cutters 10 14 and following wear of the races 69 and 74 may assume some of the outward end thrusts on the cutters 14. It will be observed that the balls 75 assisted by the balls 76 assume the outward end thrusts on the cutters 14 as well as the radial 15 thrusts on the cutters. This is important as it eliminates the necessity for thrust washers or the like at the outer ends of the cutters 14 and prevents wearing of the outer ends of the cutters and the body legs 21.

The bearing means 15 further include sleeves or rings 77 closely fitted on the pin 12 to bear inwardly against its shoulders 59. The rings 77 occur in the planes between the adjacent cutters 13 and 14. The outer corners of the rings 77 are 25 provided with relatively small ball races 78 which oppose the races 67 on the interiors of the cutters 14. Series of balls 79 are provided to cooperate with the races 67, the races 78 and the surfaces of the pin 12. The races 67 are related to the races 30 78 and the points of contact of the balls 79 with the pin 12 so that the balls assume or transmit the inward end thrusts imposed on the cutters 14, as well as radial thrusts on the cutters. From the above it will be seen that the series of balls 35 75 and 79 assisted by the balls 76 rotatably support the cutters 14 and assume or transmit all of the radial thrusts on the cutters as well as the inner and outer end thrusts on the cutters. The cutters 14 being supported by the balls 75, 76 and 40 79 are free to rotate with a minimum of friction and are dependably retained in the proper operative positions.

The improved bearing means 15 of the invention further includes spherically concaved ball 45 races 80 occurring in the corners between the surfaces or ends 49 of the pin portion 46 and the adjacent peripheral surfaces of the major body parts of the pin 12. The races 80 oppose the races 62 on the interiors of the inner cutters 13. 50 Annular series of balls 81 surround the pin 12 to cooperate with the races 62 and 80 to rotatably support the inner end portions of the cutters 13. The races 62 and 80 are related so that a line drawn through the points of contact of a 55 ball 81 with a pair of opposing races 62 and 80 is pitched relative to the pin 12 in such a manner that the series of balls 81 assume or transmit inward end thrusts on the cutters 13, as well as radial thrusts on the cutters. The cutter supporting means 15 further include series of balls 83 cooperating with the races 63 and the portions of the pin 12 of large diameter. The balls 83 also engage against spherically concaved races 84 on the inner ends of the rings 77. The relationship between the races 63 with the points of contact of the balls 83 with the pin 12 and with the races 84 is such that the balls 83 assume the outward end thrusts on the cutters 13 as well as the radial thrusts on the cutters. The innermost 70 inner cutters 13 are rotatably supported by the spaced series of balls 81 and 83 for rotation with a minimum amount of friction. As described above, the series of balls 81 and 83, respectively, assume the inward end thrusts and the outward 75

end thrusts imposed on the cutters 13 so that end thrust washers for the cutters are unnecessary. The cutters 13 are rotatably supported on the pin 12 through the balls 81 and 83 so that the inwardly projecting parts of their teeth 60 act on the formation at the bottom of the bore immediately adjacent its center.

In operation the bit is connected with the lower end of a rotary well drilling string and operated 10 in the well in accordance with the rotary method of well drilling. During operation the outer cutters 11 act on the outer portion of the well bore in an annular path to cut the bore to gauge and to assist in cutting away the formation at the 15 bottom of the bore. The inner cutters 13 and 14 follow concentric annular paths in their action on the formation to cut away the formation at the bottom of the bore. The several cutters are supported for free independent rotation about 20 their own axes. The outer cutters 11 are rotatably supported by the series of balls 44 and 45 in such a manner that the radial thrusts and the end thrusts on the cutters are transmitted through the balls. The cutters 11 are supported 25 between balls 44 and 45 so that their ends do not bear against the body wings 18 or 19 or the bushings 33 or 34 and the ends of the cutters are not subjected to wear. The annular series of balls 44 and 45 are long wearing and dependable 30 to rotatably support the cutters 11 to cut the bore to gauge for a long period of operation. The bushings 33 and 34 are fitted between the body wings 18 and 19 so that they do not have end movement or play and are held against rotation 35 by their respective lugs 35 and 40. Following extended use of the bit the bushings 33 and 34 and the series of balls 44 and 45 may be replaced.

As described in full above the inner cutters 13 and 14 are entirely supported by the series of 40 balls 81 and 83 and 15, 16 and 19, which series of balls assume all radial thrusts as well as all of the end thrusts transmitted through the cutters. The balls are long wearing and rotatably support the cutters 13 and 14 for free rotation 45 in their proper positions for a long period of operation. The adjacent cutters 13 and 14 do not bear one against the other and it is unnecessary to provide thrust washers between the adjacent cutters. It is also unnecessary to provide 50 thrust washers or thrust bearings at the inner ends of the cutters 13 or the outer ends of the cutters 14. The assembly of the several inner cutters 13 and 14, the pin 12 and the bearing means 15 is easily and quickly mounted on the 55 lower end of the body 10. The pin 12 is securely and rigidly connected with the body 10 intermediate its ends by the screw 50. The intermediate portion 46 of the pin bears against the wall of the recess or notch 48 for the transmission of 60 vertical forces. The opposite ends of the cutter carrying pin 12 are dependably secured to the legs 12 by the screws 56. The bit is inexpensive to manufacture and is easy to service and recondition for operation.

65 Having described only a typical preferred form and application of my invention I do not wish to be limited or restricted to the specific details herein set forth, but wish to reserve to myself any variations or modifications that may appear 70 to those skilled in the art or fall within the scope of the following claims.

Having described my invention, I claim:

1. A well bit including, a body, outer cutting means on the lower end of the body for cutting 75 the well bore to gauge, a supporting pin on the

lower end of the body, a roller cutter for acting on the formation at the inner portion of the bore, spaced ball races formed directly on the interior of said cutter and facing inwardly and toward the adjacent ends of the cutter, and a series of balls cooperating with each race and rotatably supporting the cutter on the said pin. 5

2. In a well bit, a body, a supporting member carried by the body, a cutter having two spaced internal races, one race facing inwardly and toward one end of the cutter, the other race facing inwardly and toward the other end of the cutter, a ball race on the member substantially opposing the first mentioned race, balls cooperating with the first mentioned race and the race on the member, a washer on the member having a ball race substantially opposing said other race, and a series of balls cooperating with said other race and the race on the washer. 10

3. In a well bit, a body, a supporting member 20 on the body having two shoulders facing in the same direction, a ball race on one shoulder, a roller cutter around the member having a race opposing the first named race, a series of balls cooperating in the said races, a ring held against the other shoulder, a second race on the interior of the cutter, and a series of balls cooperating 25 with said second race and the member and held in place by said ring.

4. In a well bit, a body, a supporting member 30 on the body having two shoulders facing in the same direction, a ball race on one shoulder, a roller cutter around the member having a race opposing the first named race, a series of balls cooperating in the said races, a second race on 35 the interior of the cutter, a series of balls cooperating with said second race and the member, a ring on the member held against the other shoulder, and a race on the ring cooperating with the second mentioned series of balls. 40

5. In a well bit, a body, a supporting pin on 45 the body having a radial shoulder, adjacent cutters surrounding the pin, races in the cutters facing inwardly and toward the adjacent ends of the cutters, a ring on the pin bearing against said shoulder, and series of balls cooperating with said races and the pin and engaging against the ring for the transmission of end thrusts from the cutters.

6. In a well bit, a body, a supporting pin on 50 the body having a radial shoulder, a ring on the pin bearing against said shoulder, a bushing on the pin, a cutter surrounding the pin, a race on the interior of the cutter facing inwardly and axially toward the ring, a series of balls cooperating with said race, the pin and the ring for the transmission of radial thrusts and end thrusts in one direction, a race on the bushing, a second race on the interior of the cutter opposing the race on the bushing, and a series of 55 balls cooperating with said second race and the race on the bushing for the transmission of radial thrusts and end thrusts in the other direction.

7. In a well bit, a body, spaced legs on the lower end of the body, a web between the legs, a separately formed cutter supporting pin, means securing the ends of the pin to the legs, a part on the pin having bearing engagement against the web, and a screw attaching said part to the 70 web. 85

8. In a well bit, a body, spaced legs on the lower end of the body, a web between the legs, the web having a flat walled notch, a cutter carrying pin, means securing the ends of the pin 75

to the legs, a part on the pin fitting said notch and means securing said part to the web.

9. In a well bit, a body, spaced legs on the lower end of the body, a web between the legs, the web having a flat walled notch, a cutter carrying pin, means securing the ends of the pin to the legs, a part on the pin fitting said notch

and means securing said part to the web, said means including a screw threaded into the said part, a member welded on the web, and a polygonal lock cooperating with correspondingly shaped openings in the screw and the member 5 to prevent unthreading of the screw.

ALFRED C. CATLAND.
